UNITED STATES PATENT OFFICE.

THOMAS F. DURHAM, OF PHILADELPHIA, PENNSYLVANIA.

SAFETY BLASTING-CARTRIDGE.

SPECIFICATION forming part of Letters Patent No. 691,367, dated January 21, 1902.

Application filed October 15, 1901. Serial No. 78,683. (No model.)

To all whom it may concern:

Be it known that I, THOMAS F. DURHAM, a citizen of the United States, residing at Philadelphia, county of Philadelphia, and State of Pennsylvania, have invented a certain new and useful Improvement in Safety Blasting-Cartridges, of which the following is a specification.

My invention relates to a new and useful improvement in safety blasting-cartridges; and this invention is intended for an improvement upon an application filed by me for safety blasting-cartridges June 11, 1901, bearing Serial No. 64,081; and the object of this my present invention is to so construct the blasting-cartridge as to enable the same to be manufactured at a comparatively small cost and still be practical in its workings. This cartridge relates to that class of blasting-cartridges in which the blasting charge is contained within an inner receptacle which is inserted within an outer receptacle filled with a fire-extinguishing agent, so that the blasting charge is entirely surrounded by a liquid or gas adapted to smother the flame arising from the explosive.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a longitudinal section of my improved cartridge. Fig. 2 is a section on the line 2 2 of Fig. 1. Fig. 3 is a perspective view of the plug for closing the lower end of the outer receptacle. Fig. 4 is a vertical section of the lower portion of the outer receptacle, showing a modified form of the plug. Fig. 5 is a perspective view of a portion of the outer and inner receptacle, the outer receptacle being broken away to show a modified form of the separating-band designed to hold the inner and outer receptacle at a distance from one another.

In my former invention, above referred to, the inner receptacle or cartridge which con-

tains the explosive was held at a distance from the walls of the outer receptacle by arms or tongues secured to the cartridge proper and coming in contact with the walls of the outer receptacle, so as to hold the cartridge at a distance from the outer receptacle, and in this former application the tube containing the explosive and outer receptacle were shown constructed of one piece, which would probably necessitate their being made in metal, which I have found by experiment to be impractical as far as the cheapness and cost of manufacture are concerned.

In this invention, A represents the inner tube or receptacle, which is adapted to contain the explosive B, and this constitutes the cartridge. C is the outer receptacle, in which the cartridge is inserted. In this inner and outer receptacle A and C, respectively, I prefer to employ a pasteboard tube, which may be made by any of the well-known methods, and the lower end of the cartridge or inner receptacle A is closed by means of the pasteboard disk or plug A', the ends of the tube A being turned over at A² for the purpose of holding the plug in place. The lower end of the outer receptacle C is also closed by a series of pasteboard disks in the form of a plug C', and the lower edge of the tube C is turned over at C² for the purpose of holding this plug in place. Upon the upper surface of the plug C' is glued or secured in any other manner a block D, and upon this block is adapted to rest the cartridge for the purpose of holding the cartridge at a distance from the bottom of the outer receptacle C. Both the inner receptacle A and outer receptacle C are immersed in a paraffin or waterproofing solution after the plugs A' and C' and the block D are secured in place. This makes the tubes or receptacles absolutely impervious to dampness.

The upper end of the tube A of the cartridge is closed by a cork E or plug of other suitable material after the explosive has been inserted, and through this cork projects the igniting device F, which may be of any construction, but being preferably an electric rod sparker, or a fuse may be used, if so desired. For the purpose of holding the cartridge at a distance from the walls of the outer receptacle C, I prefer to employ a band surrounding

the cartridge A near the top and bottom and this band having protuberances thereon adapted to come in contact with the walls of the outer receptacle.

5 I have found by experiment that the cheapest and most practical material to use is a cord or rope knotted at frequent intervals and secured around the cartridge, as illustrated at G, the knots G' serving to hold the cartridge and the outer receptacle at a distance from one another for allowing the free circulation of the liquid or gas therebetween, and this rope or cord will also form a cushion between the two receptacles. After the fire-extinguishing agent has been placed in the outer receptacle the upper end of said receptacle is closed by a cork or plug H, through which the fuse or electric wires may pass.

In Fig. 5 I have shown a modified form of the separating-band I, which may be made of cardboard to encircle the cartridge, and this band is notched or perforated at I', so as to hold the receptacles at a distance from one another, but at the same time allow the free circulation of the fire-extinguishing agent therebetween. Of course other forms of bands could be used, in which protuberances are formed thereon in a different manner.

In Fig. 4 I have shown a modification in which the plug at the lower end of the outer receptacle is formed by stamping a cardboard disk J upward in the center to form the inverted-cup-shaped projection J'. This projection will take the place of the block D, upon which rests the cartridge, and thus the plug closing the lower end of the outer receptacle and the rest for the cartridge will be formed in one piece. The lower edges of the receptacle C would be turned over at C' to hold the plug in place.

The advantage of my invention is that by constructing the receptacles of cardboard and coating them with a waterproofing solution I am enabled to manufacture them at a comparatively small cost, and by the use of the bands I provide a cheap and effective device for holding the two receptacles apart.

Of course I do not wish to be limited to the exact construction here shown, as slight modifications could be made without departing from the spirit of my invention.

Having thus fully described my invention, what I claim as new and useful is—

1. In a safety blasting-cartridge, a receptacle adapted to contain a fire-extinguishing agent, a cartridge within said receptacle, and means for exploding the cartridge in combination with bands secured around the cartridge, protuberances formed upon the bands at intervals for the purpose of holding the cartridge at a distance from the outer receptacle and allowing for the free circulation of the fire-extinguishing agent therebetween, a block secured in the lower end of the outer receptacle upon which the cartridge rests, substantially as and for the purpose specified.

2. In a safety blasting-cartridge of the char-

acter described, an outer receptacle composed of a pasteboard tube, a plug closing the lower end of said tube, a block secured to the inner face of said plug, said tube, plug and block coated with waterproofing solution, an inner receptacle adapted to contain the explosive agent, said inner receptacle composed of a pasteboard tube, a pasteboard plug closing the lower end of the same, said tube and plug coated with waterproofing solution, a band of cord or rope secured around the inner receptacle near the top and bottom of the same, said cord or rope knotted at frequent intervals, a fire-extinguishing agent adapted to be contained in the outer receptacle, substantially as and for the purpose specified.

3. In a blasting cartridge of the character described, an outer receptacle composed of a pasteboard tube, a plug of pasteboard inserted in the lower end of the tube, the lower edges of the tube being bent underneath the plug to hold the same in place, a block secured to the inner surface of the center of the plug, said tube, plug and block being coated with a waterproofing solution, an inner receptacle adapted to contain the explosive, said receptacle consisting of a pasteboard tube, a plug closing the lower end of the tube, the lower edges of the tube being turned underneath the plug, said tube and plug being coated with a waterproofing solution, bands secured around the inner receptacle near the top and bottom, protuberances formed upon said bands at intervals for the purpose of holding the two receptacles apart, fire-extinguishing agent adapted to be contained in the outer receptacle, plugs closing the inner receptacle and the outer receptacle and means for exploding the cartridge, substantially as and for the purpose specified.

4. In combination with a cartridge of the character described, bands secured around the inner receptacle, said bands consisting of cardboard, openings formed through the cardboard to allow for the free circulation of the fire-extinguishing agent, said cardboard bands being coated with a waterproofing solution, substantially as described.

5. In combination with a cartridge of the character described, a plug for closing the lower end of the outer receptacle, said plug consisting of a disk of cardboard having a protuberance extending upward in the center, upon which protuberance the inner receptacle is adapted to rest, the edges of the outer receptacle being turned underneath the disk for the purpose of holding the same in place, as specified.

In testimony whereof I have hereunto affixed my signature in the presence of two subscribing witnesses.

THOMAS F. DURHAM.
